Thomas E. Deafleld.
ATTORNEY.

UNITED STATES PATENT OFFICE.

LAURENCE A. SMITH, OF KANSAS CITY, MISSOURI.

SUPPORT FIXTURE FOR HANGINGS OR FOR CLOTHES HANGERS.

Application filed August 10, 1927. Serial No. 211,998.

This invention relates to extensible supports adapted to be used for window shades, window hangings or for closet poles for hanging clothes.

5 The invention has to do more particularly with a toggle arrangement or connection between two channels upon the ends of which are pressure clamps, the construction being such that the channels when in alignment are held rigidly as a solid unitary rod or pole between the side frames of the window or between the walls of the closet or elsewhere where a support of this character may be used.

15 Figure 1 is an elevational view of the lintel of a window with the support in position.

Figure 2 is an enlarged detail of the pressure or fixture plate.

20 Figure 3 is an edge view showing the arrangement for attaching the fixture plates to the channel bars.

Figure 4 is a sectional view taken through the channel bars.

25 Figure 5 is a top detail view of the fixture plate shown in Figure 2.

Figure 6 is an enlarged detail of the connections between the two channel bars.

30 Figure 7 is a side view showing the pressure members used for the closet fixture.

Figure 8 is a face view of the members shown in Figure 7.

Figure 9 is a side view of the closet bar or pole in position between the closet walls.

35 In the drawings, Figures 1, 2, 3, 4, 5 and 6 refer to the fixture for window hangings and window shades. Figures 7, 8 and 9 show the closet bar construction.

Referring to the drawings, at 1 is shown 40 the lintel of a window frame, the side frames being designated as 2, the hanging support of the fixture consists of a channel bar 3 and a second channel bar 4 slotted as shown at 5. The bar 3 has at its end a lug 6 which 45 has a curve shape and is adapted to engage one of the slots, as shown in Figure 1. At the outer ends of the channel bars are affixed the fixture or pressure plates 7. These plates have a flat face and are turned back 50 as shown at 7^a, to form a recess for the resilient pads preferably of rubber shown at 8^a. These pads contact the inside of the window frame, and due to the pressure imposed upon the pressure plate or the fixture plate by the 55 channel bars when in an aligned position, hold the fixture rigidly in place upon the

window frame. The manner in which the bars are placed in position will be explained. On the face of the fixture plate are attached the tube brackets 8 for curtain hanging rods, and shade brackets 9 by means of which the window shades are supported.

60 The fixture or pressure plates are removable from the channels; they are fastened to the channels in the following manner:

65 From the turned back portion 7^a of the fixture plate 7 is stamped or pressed out a tongue 10 and a support ledge or rest 11. In the ends of the channels are notch shaped apertures 12 shown in Figures 2 and 5. The 70 tongues 10 are hooked into the apertures and the bottom closed portion of the channel is supported between the rest or ledge 11. Thus the fixture plates are easily removable and are held rigidly when the support 75 members are in position.

80 The channel bars lying one within the other, as shown in Figure 4, are extended so that the fixture plates contact the side frames of the window in which the fixture support is to be placed. The support is then taken out of the window frame and extended one notch or one slot and the lug 6 inserted in the slot 5 of the opposite channel bar 4. The channel bars are then again inserted in 85 the window as close to the lintel as possible and the bars brought in alignment which extends the pressure plates or fixture plates against the frame holding the entire structure rigidly in position. The ring clamp 13 90 shown in Figures 1 and 4 is slid over the two channel bars to lock them in position.

To remove the fixture support the clamp 95 13 is slid onto the channel 3 and the bars broken from alignment, at which time the pressure upon the fixture plates is removed and the entire support easily taken down from the frame.

100 The construction of a closet pole or bar shown in Figures 7, 8, and 9 is identical to the fixture support in so far as the channel bars 3 and 4 are concerned. The channel bar 3 having the lug 6 engaging the slots 5 of the channel bar 4 and the construction held in alignment by means of a ring clamp 13, is shown in Figure 1. The pressure members 7 at the end of the channel bars are fastened to the channel bars similarly to the manner in which the fixture plates were attached except that in place of the support ledge 11, shown in Figure 3, there 105 is a cut or slot in ridge 14, formed in the 110

pressure member 7, a slot 15 which serves as a rest for the narrow side of the channel. The wide sides are vertical legs of the channel abutting upon the pressure member 7 on both sides of the pressed out ridge or raised portion 13. The tongues 10, cut out of the raised portion are identical in construction to the tongues 10 in the fixture plates of the window fixture support. Likewise the channels have notched apertures 12, shown in Figure 7 and corresponding to the apertures 12, shown in Figures 2 and 5.

Although the fixture adapted to be used in connection with the fixture support is used as a relatively simple device, it is contemplated by the invention that any suitable type of fixture may be held at the ends of the channels. Furthermore, while the invention has been adapted to but two uses, namely the window fixture support and the closet pole, it is appreciated that the toggle arrangement may as well be used in other ways and it is the purpose of the disclosure not to limit the invention to the purposes shown.

I also contemplate using my device as a lateral support in connection with construction work such as in trenches and in concrete construction for holding forms. In such cases, it would be used as a lateral support or a support for vertical walls.

The novelty of the invention lies primarily in the use of a slotted channel bar having a second bar with an engaging member adapted to be inserted in the slots of the first bar and a clamp for holding the bars when brought in alignment. Further novelty is thought to lie in the method of adapting the end pressure members by means of the tongue and support rests for the channels.

I claim as my invention:

1. In a device of the character described, two telescoped channels, said channels ad-

justable as to their combined length, pressure contacting members at the outer ends of the channels, one of said channels having a line of apertures in its bottom, a tongue at one end of the other channel adapted to be inserted through any one of the apertures of the apertured channel to produce toggle engagement between the channels, and means for holding said channels in alignment. 45

2. In a device of the character described, a pressure contacting member and a rod member detachably connected together, one of said members being formed of sheet metal and having an integral tongue and a ledge, the other member resting on said ledge and having an aperture into which the tongue extends, said tongue being removable from the aperture by relatively moving said members. 55

3. In a device of the character described, a pressure contacting member formed of sheet metal and having an integral tongue and a ledge, and a rod resting on said ledge and having an aperture into which the tongue extends for detachably holding the parts together. 65

4. In a device of the character described, a pair of telescoped channel shaped members forming a rod, one of said members having a line of apertures in its bottom, a tongue on one end of the other member adapted to project through any one of said apertures to produce toggle engagement between the members, each member being provided at its outer end with an aperture, and pressure contacting members arranged at the ends of the rod and each provided with a ledge to support the rod, and a tongue arranged on each pressure contacting member and engaging one of the apertures in the outer end of the rod for detachably connecting the 75 80 85 rod to the pressure contacting members. 70 75 80 85

LAURENCE A. SMITH.
